CALF FEEDER

Mary Bruehl, Mount Clemens, Mich.

Application May 22, 1941, Serial No. 394,603

1 Claim. (Cl. 119—71)

This invention relates to farm apparatus and particularly to equipment for use on a dairy farm.

An object of the invention is to provide a device for feeding calves, so that with its use much of the handling of the animals now necessary under present practices may be dispensed with.

When a calf is fed by the cow it is the usual practice to take the calf to its mother at regular intervals. This requires a lot of handling before the calf is old enough to be weaned. As the calf increases in size and strength it often times becomes almost unmanageable. If there are numerous calves to be taken care of it becomes a chore of considerable magnitude.

With my improved calf feeder the calves can remain in their own quarters and can be fed with great efficiency, by an inexperienced hand or by a child.

This also permits the cows to be milked in the usual manner.

Another advantage of my device is that with its use it becomes a simple matter to gradually change the calf from a liquid to a solid diet. With its use it is also possible to feed the calf skimmed milk, either with or without the addition of other foods, such as calf meal and the like.

Further objects and advantages of the invention will become apparent as the description proceeds, reference being made from time to time to the accompanying drawing, in which:

Fig. 1 is a sectional view of a device embodying my invention.

Fig. 2 is a fragmentary plan view, with parts broken away, of the device illustrated in Fig. 1.

The invention resides in the particular combination and arrangement of parts.

Referring now more particularly to the drawing, it will be understood that in the embodiment herein disclosed, my device consists generally of a receptacle 5, which is preferably made of aluminum or other suitable material, and supported as illustrated and described hereinafter, by means of a framework 6, which can be made of pieces of angle iron secured together by any suitable means.

The framework 6 has front members 7 and longer back members 8, all of which are adjustable for height as at 9, and connected to each other by cross members 10, 11 and 12. The upper cross members 12 are disposed in an inclined position and are adapted to support the

weight of the receptacle 5, which is provided with a flared rim 13.

This allows the opening of the receptacle 5 to be disposed in an angular position so that the calf can reach the interior of the receptacle more readily.

The frame 6 is provided with means 14 whereby the device may be anchored to a wall if desired.

10] On the interior of the receptacle 5 is positioned the hollow fitting 15, which comprises a convex base 16 and an angularly disposed neck 17. The base 16 is preferably removably secured to the bottom 18 of the receptacle 5 by means of bayonet slots 19, which engage suitable studs 20 fixed in the bottom of the receptacle 6. The base 16 is perforated, as at 21, so that liquid may reach its interior. The upper end of the neck 17 is reduced and flared, as at 22, and secured there- 20 to is a soft rubber member 23, which is made to simulate the teat of a cow. A tube 24 is fitted into the member 23 and extends to a point near the bottom of the receptacle 5, so that liquid may be drawn through it when the calf sucks 25 on the member 23.

On the bottom exterior of the receptacle 5, immediately beneath the fitting 15, is an electric heating element 25, which is secured to a suitable insulator 26, carried by the housing 27, the latter being held in position by the lower ends of the studs 20, heretofore described.

The fitting 15 can readily be removed so that the interior of the receptacle 5 can be washed and sterilized. In practice the fitting 15 is also removed when the calf is being taken from a purely liquid diet to a solid diet so that the transition from one diet to the other is accomplished with a minimum of disturbance to the animal's habits.

40 Having described my invention, what I claim and desire to secure by Letters Patent is:

A calf feeding device comprising the combination of a bowl-like member having an off center flat portion, means including a teat simulating member angularly secured to the inside of said bowl and covering said flat portion, a heating element housing supported on the outside of said bowl and covering said flat portion, and a heating element in said housing, adapted to applying heat to the said flat portion of said bowl.

MARY BRUEHL.
